UNITED STATES PATENT OFFICE.

FREEBORN F. RAYMOND, 2d, OF NEWTON, MASSACHUSETTS.

HEEL-NAILING MACHINE.

SPECIFICATION forming part of Letters Patent No. 377,172, dated January 31, 1888.

Application filed November 2, 1887. Serial No. 254,039. (No model.)

To all whom it may concern:

Be it known that I, FREEBORN F. RAYMOND, 2d, of Newton, in the county of Middlesex and State of Massachusetts, a citizen of the United States, have invented a new and useful Improvement in Heel-Nailing Machines, of which the following is a full, clear, and exact description, reference being had to the accompanying drawings, forming a part of this specification, in explaining its nature.

The invention relates to a heel-nailing machine provided with a solid die for centering the heel-blank and for shaping and compressing its side surfaces by lateral pressure during the attachment of the heel-blank to the soles of the boot or shoe.

The invention is illustrated as applied to a National heel-nailing machine.

In the drawings, Figure 1 is a view of a part 20 of the National machine, part in front elevation and part in vertical section, provided with my improvement. Fig. 2 is a view in plan of the table supporting the die, templet, and nail-carrier, and in horizontal section of 25 the frame of the machine upon a line immediately above the surface of the nail-carrier. Fig. 3 is a view of the parts represented in Fig. 1 at the completion of the compression of the heel-blank. Fig. 4 is a detail view illustrating the application of a top lift to the compressed heel-blank. Figs. 5 and 6 are detail views of the solid die.

Referring to the drawings, A is the cross-head of the machine. It is provided with a 35 reciprocating movement, substantially as described in the Henderson patent, No. 316,894, and it carries a rotary head, B, having four arms—first, the arm a , having a pressure-block, a' ; second, the arm a'' , having a block, a'' , carrying a gang or group of awls, A'; third, an arm, a'' , carrying a block, a'' , supporting a gang or group of drivers, a'' ; fourth, an arm, a'' , supporting a block, a'' , carrying the top-lift holder and forming a top-lift spanker.

B is a vertically-movable table. It is like that described in said Henderson patent, excepting that it has forward-extending sections b , which furnish the recesses b' for the solid die block C, and also an additional support 45 for the templet D when in operative position. This additional support is obtained by the extension of the cap-plates d . These cap-plates heretofore have not extended beyond the edge

of the templet when drawn back. Consequently the templet, when forward in its operative position, was supported at its rear end only, and was not supported by cap-plates extending from its sides. The templet D is horizontally movable in the table.

D' is the nail-carrier. This is also horizontally movable on the templet-plate, and is held in position thereon by the cap-plates d . The die-block C is of metal, and has the die-cavity d' formed therein, the side surface of which above the sole-line (indicated by Fig. 6) is of 65 the shape which it is desired to give the side surface of the heel-blank. Below the dotted line the die flares outwardly to provide a full entrance for the heel-blank to the die. The die is cut away at its front to provide a recess 70 or space, d'' , for the sole of the boot or shoe, as upon the application of pressure to the heel-blank the die is moved downward and its sides and back caused to extend below the level of the outsole. The die-block C preferably is 75 held in place in the table B by means of a spring-pin.

In operation the heel-blank is placed beneath the die-cavity and partially inserted therein, the jack carrying the boot or shoe 80 moved into position beneath it, the templet moved out into operative position to cover the upper opening, d'' , to the die, and the table moved down by the hand-lever described in said Henderson patent. The pressure-block 85 a' having been moved into position, the machine is caused to make one reciprocation.

This brings the pressure-block into contact with the templet-plate and moves it downward, also causing the table B to be moved downward and the die C to be forced upon the heel-blank and to form or shape its side surfaces and to support them while it is being vertically compressed between the templet-plate and the upper surface of the last or work-support E. 95 The table is automatically locked in its lowest position, as described in the said Henderson patent, at the end of the downward movement of the pressure-block, and it is then turned out of operative position and the awls 100 moved into operative position. The machine is again operated and the awls reciprocated and holes punctured in the compressed heel-blank. The machine again comes to rest, the awls are moved out of operative position 105 and the drivers into operative position, the

attaching-nails are fed to the templet by means of the nail-carrier, and the machine again caused to make a reciprocation, and the attaching-nails are driven into the heel and soles of the boot or shoe, and, if the heel is to be blind-nailed, are left protruding from the upper surface of the heel-blank. The table B is then released or unlatched and allowed to be moved upward sufficiently to disengage 5 the die and templet from the heel-blank, and the templet is then moved backward and the top-lift spanker and holder moved into operative position. The lift having been placed in the top-lift holder, the machine makes another reciprocation, and the top lift is spanked upon the protruding ends of the attaching-nails.

The top lift, of course, must be a trifle smaller than the upper opening, d^3 , of the die-block.

It will be seen that upon the backward movement of the templet-plate the upper surface of the inverted heel is exposed in the die for the reception of the top lift, and that upon the downward movement of the top-lift spanker 25 the table and die are caused to be again moved downward in relation to the heel-blank.

The die C may also be used for centering heel-blanks formed in any other heel-blank-forming machine, as well as for centering ordinary or unformed heel-blanks for flush-nailing, in which case the die may be made shorter or with a die-recess of less depth than that herein described.

I would say that the mechanism herein described may be used for shaping and compressing heel-blanks without attaching them to the soles of a boot or shoe, if desired, in which event the templet-plate D may be stationary, 35 or may be entirely dispensed with and the pressure-block a' be made sufficiently long to come in contact with the die-block C and close its upper opening, d^3 , upon its downward movement.

I would also say that the die-block C is removable from the table, in order that the die-blocks having die-cavities of different shapes may be substituted.

I would say, also, that the heel-blank may 50 be compressed by the die and solidified and the heel-seat formed and pricked, or pricked and loaded, without being attached, if desired.

I am aware of the patents to Bigelow, No. 105,030, dated July 5, 1870; to Hartman, No. 55 157,822, dated December 15, 1874; to Houghton, No. 180,030, dated July 18, 1876; to Glidden, No. 139,382, dated May 27, 1873, and to McKay and Fairfield, No. 153,360, dated July 21, 1874, which describe the use of various 60 forms of dies; but none of these patents shows or describes an organization of a solid die into a heel-nailing machine adapted to attach a heel-blank to the soles of a boot or shoe, and none of them shows a solid die which is closed by a horizontally-movable templet, and which die, aside from its vertical movement, is sta-

tionary during the pricking of the holes and the driving of the nails, and which is adapted to be uncovered to permit the spanking of a top lift. I therefore consider that my invention is not disclosed in these patents.

Having thus fully described my invention, I claim and desire to secure by Letters Patent of the United States—

1. In a heel-nailing machine, the combination of a reciprocating head, a rotary head supported thereby, having an arm carrying a pressure-block, an arm carrying a gang of awls, an arm carrying a gang of drivers, and an arm supporting the top-lift spanker, which are adapted to be brought successively into operative position, a last or work-support, a vertically-movable table, a solid die-block having a die-cavity, supported by said table, the sliding templet-plate D, and nail-carrier 75 D', substantially as described.

2. The combination, in a heel-attaching machine, of the table B, having a forward extension, b, and cap-plates d, with the horizontally-movable templet D, substantially as de- 90 scribed.

3. The combination of the table B, the solid die-block C, supported thereby, and the horizontally-movable templet D, also supported by said table, substantially as described.

4. The combination, in a heel-nailing machine, of the table B, having a die-block-receiving recess, b', open at its front end, with the removable die-block having the die cavity d', substantially as described.

5. The combination of a vertically-movable pressure-head, the last or work-support, the vertically-movable table B, and the solid die C, supported thereby, having the die cavity d', substantially as described.

6. The combination of the last or work-support, the vertically-movable table B, and the solid die C, having the die-cavity d' and opening d', with the top-lift-attaching device a⁸, substantially as described.

7. In a heel-attaching machine, the solid die-block C, having the die-cavity d', and the recess d², and flaring mouth, as and for the purposes described.

8. In a heel-attaching machine, the combination of the last or work-support, the vertically-movable table B, the solid die C, supported by said table and having the die-cavity d', the templet D, and a reciprocating gang or group of awls, A', substantially as described.

9. The combination of the last or work-support, the vertically-moving table B, the solid die-block C, supported by said table B and having the die-cavity d', the templet D, and the reciprocating gang of drivers a⁶, as and 125 for the purposes described.
